(57) **CLAIM**

I claim the ornamental design for a shoe outsole, as shown and described.

DESCRIPTION

FIG. 1 is a top plan view of a shoe outsole showing my new design

FIG. 2 is a bottom plan view thereof;

FIG. 3 is a right side elevational view thereof;

FIG. 4 is a left side elevational view thereof;

FIG. 5 is a front elevational view thereof;

FIG. 6 is a rear elevational view thereof;

FIG. 7 is a top plan view of a second embodiment of the shoe outsole of FIG. 1;

FIG. 8 is a bottom plan view thereof;

FIG. 9 is a right side elevational view thereof;

FIG. 10 is a left side elevational view thereof;

FIG. 11 is a front elevational view thereof; and,

FIG. 12 is a rear elevational view thereof.

The drawing disclosure of each embodiment shows the design for a shoe outsole for a right shoe. It is understood that the left shoe outsole is a mirror image thereof.

The broken lines shown in the drawings are for illustrative purposes only and form no part of the claimed design.
